UNITED STATES PATENT OFFICE

WILLIAM HARPER, OF ALBANY, OREGON, ASSIGNOR OF ONE-HALF TO HERBERT C. MORRIS, OF ALBANY, OREGON

SELF-CLEANING SAW FOR BARK-PEELING MACHINES

Application filed June 23, 1927. Serial No. 200,884.

My invention relates to bark peeling machines, as used in the pulp and paper industries and has for its primary object, the removal of the bark from round sections of logs of relatively short lengths.

The invention consists primarily of a main central framed structure in which are mounted a set of cradle like knees, upon which the log section is deposited; power means may then be set in motion for the self centering of the log and power means for the chucking of the same about its central axis; means permitting the removal of the log section after the same has been finished consists in the downward hinging of one of the sides of the cradle-like holding means to permit of the rolling of the log section from the device and power means consisting of a central shaft; means for driving the same, a series of wobble cutter heads as saws being mounted upon the shaft in spaced relationship and means preventing the deposit of removed material from between the spaced cutter heads, as saws, means being also provided for the withdrawing of the removed bark sections as by suction.

A further object of the invention consists not only in the removal of the bark, but consists also in the removal of knots and limbs and other projecting foreign matter from the body portion of the log section.

Still further objects of the device consist in providing a cradle for the reception of the log section, with means for the self and automatic centering of the log section and jaw engaging elements adapted to engage central of each of the log sections and chuck the same to permit of the power rotation of the chucks and the engaged log about a common center.

Still further objects of my invention consist in providing means for predetermining the depth of cut that the bark removing blades are to make to prevent the removal of an undue portion of the log in the peeling operation; means is also provided for the removal of the bark that may be left within the depressions within the log surface after the major portion of the bark has been removed.

Still further objects of my invention consist in providing automatic elements for throwing out the feeding elements the object of which is to prevent the overstressing of the feeding elements and to impart thereto a factor of safety.

A further object of the invention consists in providing means for the withdrawal of the removed bark portions by suction means.

With these and incidental objects in view, the invention consists in certain novel features of construction and combination of parts, the essential elements of which are set forth in the appended claims, and a preferred form of embodiment of which is hereinafter shown with reference to the drawings which accompany and form a part of this specification.

In the drawings:

Fig. 1 is a sectional, side elevation, of the assembled device, the same being taken on line AB of Fig. 2, looking in the direction indicated.

Fig. 2 is a sectional, front elevation, of the assembled device, taken on line 2—2 of Fig. 1, looking in the direction indicated.

Fig. 3 is a top, plan view, partially in section, the same being taken on line 3—3 of Fig. 2, looking in the direction indicated.

Fig. 4 is a fragmentary, side elevation, taken on line 4—4 of Fig. 1, looking in the direction indicated.

Fig. 5 is a fragmentary, side elevation, of the mechanism illustrated in Fig. 1, the same being taken on line 5—5 of Fig. 1, looking in the direction indicated.

Fig. 6 is a sectional, end view, taken on line 6—6 of Fig. 1, looking in the direction indicated.

Fig. 7 is a top, plan view, of the sub-frame upon which the motor and the cutter head is mounted for the main bark removing and peeling device.

Fig. 8 is a fragmentary, side elevation, of the bark removing cutter head and the associated elements for the removal of the finely divided fragments of bark that have the tendency to become deposited and entrapped between the elements composing the cutter head.

Fig. 9 is a detailed, end view, of the cutter head, taken on line 9—9 of Fig. 8, looking in the direction indicated.

Fig. 10 is a side elevation of the assembled device, illustrating the various drives and unit controls composing the same.

Fig. 11 is a top, plan view, of a part of the mechanism illustrated in Fig. 1, the same being taken on line 11—11 of Fig. 1, looking in the direction indicated.

Fig. 12 is a diagrammatical lay-out of a log section, illustrating the series of operations in sequence as performed thereupon.

Fig. 13 is a detailed view of the cradle mechanism.

Fig. 14 is a diagrammatical lay-out, showing how the bark is removed from depressions formed within the log surface.

Like reference characters refer to like parts throughout the several views.

The machine in the illustrative form of embodiment disclosed herein is designed more especially for use in the pulp and paper industry, however, certain features of the machine and the functions to be performed thereby may be used to advantage in various other branches of industry, the accompanying drawings show the invention in a preferred form adapted to the particular requirements of a pulp and paper mill, but it is to be understood that it is not intended to limit the invention to such use as it may well be adapted to analogous and other uses.

Described in general terms the machine is as follows: A log section to be barked is rolled down the runway 1, shown in dotted lines in Fig. 1, and rolls within a cradle composed of arms 2 and 3. The arm 3 is preferably made longer than the arm 2, to prevent the momentum of the log section carrying the same out of the cradle. When the log section comes to rest within the cradle, composed of the arms 2 and 3, the next step in its operation is to chuck the log section and impart rotation thereto. The cradle arms 2 and 3 are disposed upon vertical stems, as shaft 4, which are threaded on their outer surface, as illustrated at 5, which is in threaded engagement with the hub of the worm wheels 6. Worms 7 and 8, illustrated in Fig. 2, coact with the worm wheels in working relationship with the thread disposed about the stems 5, and the rotation of the worm wheel with the worm, raises the cradle and the stems vertically. Power of rotation is imparted to the worms 7 and 8 through the driving element 9, illustrated in Fig. 2, the shaft 10 being rotated by the prime mover, as an electric motor 11. Secured to each of the shafts of the worms 7 and 8 are bevel gears 12 and 13 which are in working relationship with bevel gears 14 and 15 disposed adjacent the lower ends of the vertical shafts 16 and 17. It is highly desirable to maintain each side of the cradle at the same

starting elevation. Upon the lowering of the cradle elements to the initial starting position, each side of the same is actuated through the action of the worm and the worm wheel. Through the medium of the clutches 18 and 19 each side of the cradle is returned to the zero or starting position. To permit of the freeing of the log from the cradle, when the cradle has been lowered to the full zero position, as illustrated in Fig. 13, the locking pawl 20 hinged about the supporting pin 21 engages with the table 22 and unlatches the locking end 23 of the locking pawl from engagement with the lower end 24 of the arm 3 of the cradle thus permitting a hinging down of the arm 3 thus permitting the log section to roll freely from the cradle. A spring 25 normally maintains the arm 3 in raised position when the arm is unloaded, or without the weight of the log section thereupon. The spring 25 is secured at its fixed end to the stem 5, by being inserted within a slot 26. The upper end of the spring is disposed beneath the stud 27 and operates there against.

To permit of the quick centering of the log section, the vertical shafts 16 and 17 have bevel gears 28 and 29 disposed at their upper ends which coact with bevel gears 30 and 31. Bevel gears 30 and 31 are secured to shafts 32 and 33 upon which worms are disposed which are adapted to engagement with the worm wheels 34 and 35. The worm wheels are in threaded engagement with the threaded stems 36 and 37. The threaded stems 36 and 37 pass through the housing 38 and 39 and as the worm wheels 34 and 35 are rotated, the shafts 36 and 37 are actuated. Engaging heads 40 and 41 are disposed respectively upon the lower ends of the stems 36 and 37 and are adapted to engage the upper side of the log section, being centered between the heads 40 and 41 and the cradle arms 2 and 3. When rotation is imparted to the shaft 10, the cradle sections are raised and simultaneously therewith the heads 40 and 41 are lowered at substantially the same rate of speed so that the log sections, irrespective of diameter, will be substantially centered between the chucking faces 42 and 43. If the log section is smaller at one end than at the other, the clutch 18 or the clutch 19 will slip until the oppositely disposed engaging head has been made to engage the upper side of the log section at which time the operator will manipulate the clutch lever 44 secured on its inner end to the journal pin 45 and the connecting rod 46 will manipulate the clutch 47. The operator of the device stands upon the operating platform 48, illustrated in Fig. 12, and operating switches are disposed upon the switch board 49, which are so located as to be easily accessible to the operator of the device. The electric motor 50, illustrated in Fig. 2, is wired to the switches disposed upon

the switch board 49. Directly connected to the shaft 51 of the motor 50 is a driving shaft 52 secured within bearings 53 and 54 of the main frame of the machine 55. Driving elements shown in the drawings, as chains 56 and 57, connect with stub shafts 58 and 59. Mounted upon the shafts 58 and 59 are gears 60 and 61. These gears are in registerable alignment and in working relationship with elongated gears 62 and 63. Threads 64 and 65 are formed upon the inner end of the gears 62 and 63 which are in threaded relationship with the hubs 66 and 67 disposed within the side walls of the frame 55 and the gear elements 62 and 63 as rotated have lateral movement imparted thereto, and lateral movement is also imparted to the chuck engaging faces 42 and 43 because of the threaded engagement with the hubs 66 and 67. When the motor is running in its forward position, the chuck faces will be made to engage the faces of the log section and when the motor is rotated in the opposite direction, the chuck faces will be made to disengage the log section. After the log section has been substantially centered and the chuck faces have been made to engage the opposite end sections of the log, the prime mover 11 is operated in the reverse direction to disengage the engaging heads 40 and 41 and the cradle supports from the log which will then be free to rotate. The clutch engaging faces 42 and 43 are carried upon spindles, one of which runs entirely through the gear element 62, as illustrated in Fig. 2, and has mounted upon its outer end a sprocket 68 which has associated therewith a driving element, as a chain 69. The chain 69 is in working relationship with the sprocket 70, illustrated in Fig. 2, and a prime mover 71 operates through a speed reduction box 72; the desired speed being imparted to the log, to be operated upon, by the shifting of the speed elements within the speed reduction box 72 by the manipulation of the gear shifting lever 73. A clutch 74 mounted upon the shaft, of the electric motor 71 is adapted for manipulation through the foot lever 75 so that the clutch may be thrown into and out of engagement by the depressing of the foot lever 75. As the log section is rotated, the bark removing elements are made to engage therewith.

In Fig. 1, the log section is shown in dotted position at 76. An inclined guideway 77 mounted upon the side wall 78 of the main frame of the machine, carries a super frame 79, mounted upon trunnion wheels 80 and 81. The same is substantially balanced through the counterweight 82, suspended by a flexible element 83, running over the grooved pulley 84 and is then connected to the underside of the frame through a guideway 85. The guideway 85 is positioned upon the adjusting rod 86. The adjusting rod 86 is threaded on its outer end and passes

through a worm wheel 87, and is in threaded relation therewith. The worm wheel is held within limits of movement through the action of hubs 88 and 89, mounted on the underside of the super frame 79. Power of rotation is imparted to the worm wheel 87 through the worm 90. The guideway 85 is mounted upon the lower end of the adjusting and positioning rod 86 and is limited in its movement through the action of collars 91 and 92. The collars 91 and 92 permit of a partial movement of the guideway 85 and of the super frame, relative to the positioning and adjusting rod 86. A prime mover, as an electric motor 93, is secured to the secondary frame 110 and driving elements 94 and 95, as illustrated in Fig. 3, pass about pulleys or sprockets upon either end of the shaft of the motor and are adapted to drive the arbor 96 mounted within suitable bearings within the secondary frame 110. The outer surface is removed from the log section by wabblesaws or dado saws 97, mounted upon a mandrel or arbor 96 and are in spaced relationship thereupon and are so held by spacing collars 98. The saws being inclined at an angle to the central longitudinal axis of the arbor.

There is always a tendency for materials of this kind being removed to build up between the saws and prevent the efficient cutting of the saws; to prevent this, a second arbor 98A is mounted within a suitable housing bearing of the secondary frame 110, and is adapted to being driven by the driving elements as chains 99 and 100, as illustrated in Fig. 3; saws are also mounted upon this mandrel and are in spaced relationship upon arbor 98 by spacing collars 101 thereupon and of like width to the spacing collars disposed upon arbor 96 and the saws 102 are made to engage and operate between the saws disposed upon the opposite arbor in order to remove any deposits of cut or foreign material that is deposited therebetween. The secondary frame 110 is mounted upon the super frame 79 and is maintained in position through the action of a king bolt 103, illustrated in Fig. 7. An arcuate slot 104 is disposed in the upper end of the secondary frame 110 and articulates about a pin 105 disposed within the slot 104. The reason for moving the secondary frame and the arbor disposed thereupon is to compensate for the taper of the log section and to permit the removal of the outer surface parallel to the slope of the log. The secondary frame 110 is positioned through the action of the hand wheel 106 operating the shaft 107. The shaft 107 carries a worm 108 that coacts with a rack 109 disposed in registerable alignment therewith and mounted upon the rear of the secondary frame 110. This permits of an accurate adjustment of the cutter heads to that of the log section and the difference

in diameter of the log is compensated for by the movement of the super frame relative to the main frame 78 of the machine.

It is highly desirable and necessary in devices of this kind to provide means for regulating the depth of cut of the wabble saws, in order to prevent the removal of the pulp making sections of the log and to remove practically all of the bark therefrom.

10 It is necessary therefore, as illustrated in Fig. 9, to provide working elements for predetermining the depth of cut of the saws, determined by the thickness of the bark which is the controlling factor. The shaft 96 runs transversely of the cutting head upon which the wabble saws are mounted. Disposed central of the shaft 96, is the depth roller 111 disposed between the side frames 112 which act as a head of rotation as illustrated in Fig. 9.

15 To lessen the friction upon the depth roller 111, roller bearings 114 are disposed between the depth roller 111 and the side frames 112. The operator of the device manipulates the hand wheel 115, as illustrated in Fig. 8, and moves the side frames 112 within which the hubs 113 are positioned. The slots 115A disposed within the side frames permit of the positioning of the depth roller 111 upon the outside surface of the log, determines the depth to which the wabble saws 97 may penetrate the outside surface of the log. The hand wheel 115 positions the side frames 112 by threaded engagement of the threads disposed upon the shaft 116 with that of the housing 117. A dovetail joint 118 is disposed between the base of the side frames 112 and the secondary frame 110. I have placed a hood 119, illustrated in Fig. 12, over the primary cutter heads having a flexible tube 120 leading therefrom and connecting to a source of suction not here shown, but which may be of any desired suction elements that are suitable for such purposes. The operation thus described leaves an unpeeled section of log disposed between the ends thereof around its outer surface; to remove this unpeeled portion, I have provided a second series of saws 121, mounted upon an arbor 126, illustrated in Fig. 1, the same being driven by a driving element 122 through the medium of a prime mover, as an electric motor 123, the same being adapted to being raised and lowered through the threaded supporting rods 124 and 124A, the prime mover and the head being supported through a bracket 125 that is in slidable relationship with the main frame of the device. A vertical movement being imparted to the assembled unit by imparting rotation to the shafts 124A and 124 which are respectively threaded through the gears 170 and 171 disposed upon the top of housing 128. Where it is found necessary to remove knots or other projecting surfaces from the log section, as illustrated in Fig. 13, at 129, I have disposed upon

the front of the machine a third set of dado or wabble saws 130, mounted upon the arbor 131, the same being driven by the driving element 132, power being furnished by the prime mover, as an electric motor 133. This unit is supported upon the cross frame 134, illustrated in Fig. 1 and in Fig. 5, and the same is adapted to being raised and lowered upon the side frames of the machine. This being accomplished through the threaded relationship with the gears 148 and 149 disposed upon the upper side of the frame member 128, the same being manipulated by the operator of the device through the control lever 139, illustrated in Fig. 10 and in Fig. 2. The control lever 139 is connected to the bell crank 140 through the link 141, the same actuating the clutch rod 142, illustrated in Fig. 11. This is adapted to throw the clutch gears 143 and 144 into and out of engagement with the driving bevel gear 145. The clutch gears 143 and 144 are mounted upon the shaft 146 and when the same has rotation imparted thereto, the gears 147 and 147A are made to coact with bevel gears 148 and 149, mounted upon the threaded supporting rods 135 and 136 so that when the shaft 146 is driven in one direction, the frame 134 and the elements associated therewith will be lowered and when the shaft 146 is driven in the opposite direction the frame 134 and the associated elements will be raised. This adjustment is provided in advance of the projection 129 to be removed reaching the cutter heads, the purpose of which is to remove the projection 129 to the depth predetermined by the positioning of the cutter head 130, by the operator of the device through the operation of the control lever 139.

As illustrated in Fig. 14, depressions 147B may be found in the outer surface of the log section and to remove the bark therefrom I have provided a third unit of wabble saws 148B, as illustrated in Fig. 2, the same being mounted upon shafts and spaced apart by collars. This unit is carried within side frames 149B and 150B in hinged relationship and slideable upon the cross shaft 151. The cross shaft 151, as illustrated in Fig. 4, is mounted within the frame 152, which is adapted to being raised and lowered through the action of the threaded supporting rods 153 and 154. A prime mover 155 is mounted upon the frame 152 and drives the arbor through the driving element 156. The side frames 149B and 150B are slideable upon the cross shaft 151 and the same may be positioned by laterally moving the same relative to cross shaft 151 by the operator engaging hand lever 157 and moving the same laterally of the shaft 151. A prime mover for furnishing power for raising and lowering the different heads disposed within the frame, is mounted upon the top frame 128 as shown at 130

157A and the same drives the driving chain 158, as illustrated in Fig. 11. The driving chain 158 drives a jack shaft 159 upon which are mounted bevel gears 145 and 160 each of these bevel gears run continuously through the operation of the prime mover 157A. A set of bevel gears 161 and 162 are slidably disposed upon the shaft 163 and the same are adapted to having longitudinal movement 5 imparted thereto and rotation to the shaft through the action of the operating lever 164, as illustrated in Fig. 12. The pull rod 165 connects with the bell crank 166 disposed at the upper end thereof which is mounted upon the top frame member 128 and the bevel gears 161 and 162 are adapted to longitudinal movement and to being manipulated through the pull lever 164 and the connecting links disposed therebetween and the yoke 167. Disposed upon the outer ends of the shaft 163 are bevel gears 168 and 169 which coact with bevel gears 170 and 171 that are secured to the supporting and adjusting rods 124 and 124A adapted to raise and lower the bracket 25 125. When the cutter head for removing the bark within the depression 147 has been lowered to the desired position, through the manipulation of the lever 157, the cutter head may then be moved laterally until all of the 30 bark disposed within the depression has been removed through the action of the cutter head. Disposed upon the actuating clutch rod 142 is a solenoid 175 which normally rides upon the frame of the machine and is secured 35 thereto, the clutch rod 142 passing therethrough and acts as the core of the solenoid. Referring to Fig. 5 the threaded supporting rod 136 has a contact collar 178 disposed thereupon which makes an electric contact 40 with contact bar 177. This contact is made when the frame 134 has been actuated into the full cutting position. The completion of the electric current through the contact bar 177 and the conductor 179 for supplying electric 45 energy from a source not here shown, energizes the solenoid 175 and actuates the core 176 thereby disengaging the driving elements 143, 144 and 145.

I have shown in Fig. 11 and in Fig. 6 and in 50 Fig. 8, like actuating devices for the prevention of over feeding of the feeding elements but the same are not described in detail as they are for the same purpose and operate in a similar manner to that just described.

55 Disposed upon the adjusting rod 86 is a collar 178 which is placed in a fixed position thereupon and when the secondary frame 110 is actuated, the electric contact bar 177 engages with the collar and the same is caused to complete the electric circuit through the bar 177 and the electric conductor 179 passes the current through the solenoid 175 and energizes the same causing the core 176 of the 60 solenoid to actuate the clutch driving element

and to disengage the same, as illustrated in Fig. 6.

While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claims which follow.

What I claim is:—

1. In a machine of the class described, a main framed structure, a pair of cradle arms disposed upon threaded stems, cooperating elements for raising and lowering each pair of cradle arms, one side of each pair of arms being hinged relative to the other and to the stem, a pair of movable heads superposed above the cradle arms and in registerable alignment therewith and power means for raising and lowering the cradle arms and the heads simultaneously.

2. In a machine of the class described, pairs of cradle arms, one arm of each pair being longer than the oppositely disposed arm of the same pair and in hinged relation with the opposite arm, engaging heads superposed the cradle arms, manipulative means for raising and lowering the cradle arms and the heads simultaneously to center a log section therebetween, chucking elements for engaging the end sections of the log when centered and power means for rotating the chucking elements and the log at predetermined rates of rotation.

3. In a machine of the class described, a framed structure, cooperating centering elements for positioning a log section central to chucking elements, power means for engaging the chucking elements central of the end sections of the log, power means for rotating the log section when chucked, power means for removing projections outwardly disposed upon the surface of the log section, power means for removing a portion of the outer surface of the log parallel with the slope of the log for a predetermined depth and means for lowering the log section from the chucks and discharging the same from the supporting elements.

4. In a machine of the class described, a main framed structure, a superposed frame cooperating with the main frame, a cutter head cooperating with the superposed frame, power means for driving the cutter head associated with the superposed frame, cooperating elements adapted for moving the cutter head back and forth upon the main frame and means for imparting a pivotal movement to the superposed frame.

5. In a machine of the class described, a superposed frame cooperating with the main frame of the device, and outwardly extending from one side of the main frame, a secondary frame carried upon the superposed

frame and a cutter head journaled within the secondary frame, said cutter head being composed of a multiple of saws mounted in spaced relation upon an arbor and standing at an angle to a vertical line passing longitudinally of the center line of the cutter head, power means for driving the cutter head, means for imparting a lateral movement to the cutter head relative to that of the superposed frame and means for partially rotating the secondary frame relative to the superposed frame.

6. In a machine of the class described, a cutter head mounted relative to a supporting frame, said cutter head comprising an arbor, angle collars disposed upon the arbor having saws disposed therebetween, power means for driving the arbor and saws, means for imparting lateral movement to the cutter head, means for partially rotating one end of the frame supporting the cutter head about a pivotal bearing provided at the other end thereof and a depth roller for predetermining the depth of cut to be made by the cutter head.

7. In a machine of the class described, a cutter head comprising an arbor, angle collars disposed upon the arbor and in spaced relation thereupon and having cutter elements disposed upon the arbor and between the angle collars, power means for driving the arbor, a secondary arbor having cutter elements mounted thereupon and adapted to run between the cutter elements disposed upon the first mentioned arbor, means for driving the secondary arbor, means for imparting lateral movement to the supporting elements and means for partially rotating the supporting elements.

8. In a machine of the class described, a cutter head comprising of a multiple of cutter elements, spaced in parallel relation upon an arbor, elements adapted to run between the cutting elements of the cutter head, adapted to remove deposits formed therebetween, driving elements for the associated cutting elements of the cutter head and the cleaning elements, a supporting structure for the cutting elements, means for imparting longitudinal movement to the cutter head, and to impart partial rotation to the supporting structure and means for predetermining the depth of cut to be made by the cutter head.

9. In a machine of the class described, a main frame, log centering and chucking elements adjustably disposed within the frame, means for driving the chucking elements at a predetermined rate of speed, cutter heads for removing the outer surface of a log parallel to the slope of the log section, to a predetermined depth, chucking within the chucking faces, means for removing any projections on the surface of the log in advance of removing the surface of the log and means

for surfacing depressions disposed within the face of the log.

10. A machine of the class described, which comprises mechanism for supporting a log whereby it may be rotated upon its axis including means affording such rotation, mechanism for axially positioning a log relative to the supporting mechanism aforesaid, a plurality of spaced rotary cutter elements adapted for engaging the outer or bark surface of a log supported in the aforesaid supporting mechanism, a plurality of rotating elements adjacent said cutter elements each of which revolves between two adjacent of the aforesaid rotary cutter elements and forming a means for cleaning and removing substances collecting between the aforesaid rotary cutter elements.
